J. B. STOBAEUS,

APPARATUS FOR REGULATING FLUID PRESSURE.

No. 379,667.

Patented Mar. 20, 1888.

his ATTORNEY.

UNITED STATES PATENT OFFICE.

JOHN B. STOBAEUS, OF NEWARK, NEW JERSEY.

APPARATUS FOR REGULATING FLUID-PRESSURE.

SPECIFICATION forming part of Letters Patent No. 379,667, dated March 20, 1888.

Application filed August 25, 1886. Serial No. 211,814. (No model.)

To all whom it may concern:

Be it known that I, JOHN B. STOBAEUS, a citizen of the United States, and a resident of Newark, in the county of Essex and State of New Jersey, have invented new and useful Improvements in Apparatus for Regulating Fluid-Pressure, of which the following is a specification.

My invention relates to improvements in apparatus for regulating fluid-pressure, and in particular to such as are used in keeping beer in kegs under a constant low pressure of carbonic-acid gas supplied from flasks containing liquid carbonic acid under a high pressure. I have found that the operation of such apparatus is rendered uncertain and unreliable by particles of dirt entering the regulating valve, or by carbonic-acid snow formed during the passage of the acid from the flask to the low-pressure chamber.

The object of my invention is to prevent those causes of unreliability; and it consists, essentially, in placing a permeable mass into the pipe leading from the flask to the regulating-valve, in placing a wire-gauze diaphragm across the passage from the flask to the valve, and in a check-valve connected with the discharge-passage of the regulating-valve.

In the annexed drawings, Figure 1 is a sectional view showing part of a reducing-valve, together with the supply and discharge pipes of the same. Fig. 2 is an end view of the coupling to the left of Fig. 1; Fig. 3, a section through *xx* of Fig. 1. Fig. 4 shows a piece of wire-gauze from which the coil, Fig. 5, is formed. Fig. 6 shows the apparatus connected with a carbonic-acid flask and with two kegs.

Similar letters refer to similar parts throughout the several views.

The reducing-valve shown in elevation in Fig. 6 and in part in Fig. 1 is of the construction shown and described in United States Letters Patent No. 334,714, dated January 19, 1886.

A represents the casing of the valve; B, the diaphragm; G, Fig. 6, the lower shell; C, the low-pressure chamber formed by the casing A and the diaphragm B.

E is a hollow cross screwed into the casing A. One of its hollow arms, *a*, is threaded for the reception of the valve-plug D, which by

its threaded socket *e* is connected with the supply-pipe *p*. The opposite arm, *b*, contains the discharge-channel *f*. The hollow arm *c* leads into the low-pressure chamber C, and to the hollow arm *d* a pressure-gage, Q, is attached. The valve-plug D has a narrow channel, *g*, leading to the valve-nozzle *k*, the end face of which forms the valve-seat. *l* is a lever pivoted to the valve-plug at *m*, and containing the valve-disk.

One end of the supply-pipe *p*, connecting the reducing-valve with the flask P, Fig. 6, is screwed into the valve-plug D, while the other end is connected with the discharge-valve F of the flask P by means of a union-joint consisting of the flanged end *h* of the pipe *p*, the nut *n*, and a corresponding threaded part on the eduction-valve F.

As shown in Fig. 1, the flanged end *h* of the pipe *p* is recessed for the reception of a lead washer, *i*, into which a wire-gauze disk or diaphragm, *j*, is pressed, which acts as a strainer. The bore of the pipe *p* is narrowed at the end entering the plug D, and into the remaining wider part of the bore is inserted a core of coiled wire-gauze, *w*. (Shown in perspective in Fig. 5.) It is made by closely coiling a square piece of wire-gauze, *v*, Fig. 4. This wire-gauze coil is a coherent permeable mass acting as a filter to prevent the passage of dirt into the reducing-valve, and it likewise prevents the formation of carbonic-acid snow by giving up its stored heat in case of a sudden rush of gas, and taking up or restoring heat from the atmosphere through the pipe *p* under ordinary circumstances, when little or no gas is passing through.

To prevent the passage of dirt into the valve-chamber through the discharge-channel *f*, I provide a check-valve formed of a rubber band, *r*, stretched across the outer end of the channel *f*, and secured by a wire, *s*, or by any other suitable means.

Fig. 1 shows the rubber distended by the pressure of the gas, so as to allow the gas to pass through laterally, the rubber band being not much wider than the bore of the channel *f*. When the pressure is taken off, the band contracts and covers the opening and prevents backflow, which might cause dirt to enter the valve-chamber.

The end of the arm *b* to which the check-valve is secured is threaded and receives a cap or reducer, *t*, into which a hose-connection, *q*, is screwed. This connecting-piece *q* may be branched, as shown in Fig. 6, so as to afford means for connecting several kegs, *H I*, with the same flask, *P*, through rubber tubes *u*.

The valves used for regulating the supply of carbonic acid gas at a pressure of a few 10 pounds from flasks containing liquid carbonic acid under a pressure of from six hundred to twelve hundred pounds have necessarily very narrow passages, and small particles of dirt or of carbonic-acid snow are apt to obstruct the 15 passages, or, what is more dangerous, to prevent the closing of the valve, thus subjecting the kegs to excessive pressure. By the above-described improvements these difficulties are avoided and the apparatus for regulating fluid-20 pressure is made perfectly reliable. Should the permeable mass in the pipe *p* become clogged, the pipe *p* can be readily removed and exchanged or a new filter placed into the same.

I am aware that prior to my invention gas-25 regulators have been provided with filtering boxes or receptacles for loose material, such as charcoal, lime, pumice-stone, and hemp or other fibrous material, through which the gas passes on its way to the regulator. Such ar-30 rangement, however, is not suitable for apparatus which regulate the flow of gas from a very high pressure, like that of liquid carbonic acid, to a space where a pressure of a few pounds is to be maintained. The great differ-35 ence of pressure to be maintained by the valve would soon either cause a channel or channels to be formed in loose material used for fil-

tering, or, if soft fibrous material should be used, it would be compressed. Such channels cannot be formed in a coherent permeable 40 mass, such as wire-gauze; neither can it be compressed so as to close up.

What I claim as my invention, and desire to secure by Letters Patent, is—

1. The combination, with a fluid-pressure 45 regulator and its supply and discharge pipes, of a coil of metal gauze placed within the supply-pipe and a check-valve consisting of a rubber band stretched across the discharge-channel, substantially as and for the purpose 50 specified.

2. The combination of a receptacle for liquefied gas, an eduction-valve, a pressure-regulator, a pipe connecting the eduction-valve with the regulator, a coherent permeable mass 55 placed within this connecting-pipe, and a check-valve in the discharge-pipe of the regulator, substantially as and for the purpose specified.

3. The combination of the receptacle *P*, for 60 liquefied gas, the eduction-valve *F*, the pipe *p*, wire-gauze diaphragm *j*, wire-gauze coil *w*, placed within the pipe *p*, a fluid-pressure regulator, and a rubber check-valve, *r*, in the discharge-channel *f*, substantially as and for the 65 purpose specified.

In testimony that I claim the foregoing as my invention I have signed my name, in the presence of two witnesses, this 23d day of August, 1886.

JOHN B. STOBAEUS.
